CLAIM

The ornamental design for a batter separator, as shown and described.

DESCRIPTION

FIG. 1 is a front, left, top perspective view of a batter separator, showing my new design;

FIG. 2 is a rear, bottom perspective view thereof;

FIG. 3 is a rear, right, top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a partial enlarged view of FIG. 1;

FIG. 11 is a partial enlarged view of FIG. 1;

FIG. 12 is a partial enlarged view of FIG. 2;

FIG. 13 is a partial enlarged view of FIG. 3; and,

FIG. 14 is a partial enlarged view of FIG. 4.

The dashed broken lines in the figures are for the purposes of illustrating portions of the batter separator and form no part of the claimed design.

The dash-dot-dash broken lines are for notating enlarged views and form no part of the claimed design.
